INCLINOMETER

Frank C. Ostheimer, Ville Platte, La.

Application August 9, 1945, Serial No. 609,771

7 Claims. (Cl. 33—205)

1

My invention relates to apparatus for determining deviation from the vertical of bore holes in the earth.

In drilling oil wells, crooked holes or holes which deviate materially from the vertical, cause excessive wear upon the well casing, the drill stem string, the production tubing and the pump actuating string of sucker rods. They may also require the use of excessive power in pumping a well, and often result in the drilling string being twisted in two.

In order to determine the path of the drill bit, it is now common practice to periodically run inclination tests or surveys of the well being drilled. One common manner of making such tests is to lower a partially filled bottle of sulphuric acid into the well, and to let it remain stationary for a sufficient period of time for the acid to etch the bottle wall. This method requires the cessation of drilling operation for a considerable period of time for each test, in order to give the acid time to etch the bottle. It also requires the provision of new test bottles.

One object of the present invention is to provide an inclination testing apparatus, which omits the use of any etching acid, and therefore saves the time usually required for waiting upon the acid to act.

Another object is to provide a testing device which may be "run" in the same manner as is the "acid bottle."

A further object is to provide a liquid-type testing apparatus which may be used repeatedly without replacement of the liquid container.

A still further object is to provide a device of this class which has few moving parts to become worn or which might get out of order.

Another object is to provide an inclinometer or declinometer which is simple to read after the test has been made, and which requires no special or technical training on the part of the operator.

Another object will be apparent from the following description when taken in conjunction with the accompanying two sheets of drawings, wherein:

Figure 1 is a fragmentary vertical sectional view of a cased well, showing the device operatively positioned therein;

Figure 2 is a horizontal sectional view taken substantially along the line 2—2 of Fig. 1, earth and the well casing having been omitted;

Figure 3 is a vertical sectional view of the device, taken substantially along the line 3—3 of Fig. 2; and

2

Figures 4, 5, 6 and 7 are horizontal sectional views taken substantially along the lines 4—4, 5—5, 6—6, and 7—7 respectively.

Like characters of reference designate like parts in all of the figures wherein they occur.

In the drawings:

The reference numeral 1 designates a portion of the earth through which has been drilled a bore hole or well which has been provided with a usual well casing section 2. The testing portion of the device is indicated, as a whole, by the reference numeral 3, and is supported upon a threaded rod 4. The rod 4 is rigidly positioned between two stem sections 5 and 6 which may well be formed of usual rotary drill stem, or any other suitable pipe or rod which will furnish sufficient weight to sink rapidly through any fluid, such as drilling mud, which is usually present in the well casing 2. The stem sections 5 and 6 are equipped with a plurality of usual outwardly extending spring fingers or bowed ribs 7 which are adapted to frictionally engage the well casing 2, while the apparatus is being lowered therethrough. The fingers 7 are for the purpose of preventing rotation of the device in the well casing during the lowering operation.

The testing portion 3 of the apparatus is best detailed in Fig. 3, and includes:

A cylindrical transparent body 10 having an axial bore 11 to permit passage therethrough of the above mentioned rod 4. The lower end of the body is seated upon suitable packing 12 in an annular groove 13 in the upper surface of a base fitting 14 which is rigidly engaged with the rod 4. The upper surface of the fitting 14 is further provided with a deeper annular groove 15 which is narrower than the groove 13 but concentric therewith. The transparent body 10 has a plurality of radially spaced longitudinally extending through bores 16, the lower ends of which communicate with the groove 15 in the base fitting.

The upper end of the transparent body 10 is seated against a packing ring 17 in an annular groove 18 in the lower surface of a tubular fitting 19 threadedly engaged upon the rod 4. The upper fitting 19 has a plurality of radially spaced longitudinally extending through bores 20, which are preferably smaller in diameter than the bores 16 in the transparent body 10, and each of which communicates with one of the bores 16.

The annular groove 15 in the base fitting 14, and the radially spaced bores 16 in the transparent body 10, are adapted to receive a liquid 21 which only partially fills the bores 16.

The testing apparatus 3 further includes a tube valve housing 22 having its lower end seated upon the fitting 19, and having its upper end engaged with the rod 4. The housing 22 provides an annular space 23 around the rod 4 for workably enclosing an annular ring-type valve 24 adapted when seated downwardly to hermetically close the upper ends of all of the vertical bores 20 in the upper fitting 19.

The valve ring 24 has at least two upwardly extending valve stems or rods 25, each of which slidably passes upwardly through the upper end of the housing 22, and terminates thereabove in an enlarged head 26. Compression springs 27 are provided around the stems 25 in the housing 22 to urge the valve ring 24 toward a seated position, and to normally hold the same seated. Upstanding rod guide lugs 28 are provided on the upper end of the housing 22.

As a means for holding the valve ring 24 in an unseated position, each of the stems 25 has a side notch 29, and the notches are each adapted to receive one edge of a latch member 30. The two latch members 30 have one end of each pivotally mounted upon pivot pins 31 carried by the upper ends of two upstanding lugs or projections 32 also carried by the upper end of the housing 22. The latch members 30 are adapted to swing over the upper surfaces of the lugs 28 and to engage in the notches 29 to prevent the springs 27 from causing downward movement of the stems and consequently the valve 24.

Before the clevis is lowered into a well, the valve stems 25 are raised, and the latch members 30 are inserted into the notches 29. Consequently, if the well deviates from a truly vertical position at any point, the liquid 21 in the vertical bores 16 will seek different levels in the bores according to the angle from the vertical at which the device is disposed in the well. The liquid is free to gravitate and seek common levels in the bores 16, due to the fact that the smaller bores 20 thereabove all open into the air chamber 23. It is obvious, however, that should the smaller vertical bores 20 all be simultaneously closed, an air-lock would be created in the bores 16 above the liquid level, and the liquid would then be held against any flowing movement in the bores. The ring type valve 24 is provided for the purpose of closing said bores 20, and thus creating such an air lock in the bores 16. It is apparent that should the latch members 30 be removed from their notches 29, the springs 27 will instantly close the ring valve 24, and create such an air lock.

As a means for selectively and simultaneously swinging the two-latch members 30 out of their notches 29, while the device is in the well, the following described mechanism is provided.

Above the latches 30 and below the enlargement or heads 26 on the stems 25, the rod 4 is surrounded by a flat disk 35 which is suitably perforated to freely surround the rod 4 and the two stems 25. The nether face of the disk 35 is provided with two depending wedges 36 having tapered surfaces 37 which lie above the notch engaging edges of the two latch members 30. The disk 35 is free to move vertically, and when forced downwardly, the tapered surfaces 37 of the wedges 36 are adapted to contact the notch engaging edges of the latch members 30 and move the latches out of the notches 29.

In operation, the testing portion 3 of the device is mounted between the two stem sections 5 and 6, as shown in Fig. 1, and the upper stem sec-

tion 5 is connected to the lower end 8 of the rod string. Before being inserted in the upper end of the well, the valve stems 25 are manually raised, and the latch members 30 are engaged in the side notches 29. This operation latches the ring valve 24 in an unseated position, which permits a free flow of air from the air chamber 23 through the upper vertical bores 20 to the lower vertical bores 16, thus permitting the liquid 21 to seek a common level in the bores 16.

The device is then lowered into the well casing 2 which is normally filled with drilling fluid, and during the lowering operation, the drilling fluid acts to hold the disk 35 at the upper end of its permitted travel, or against the heads 26 on the valve stems 25. This is due to the resistance of the drilling fluid to movement of the disk therethrough.

When the device has been lowered to the position in the well at which it is desired the test shall be made, the rod string and consequently the whole device, is suddenly raised a few inches. This movement causes the disk 35 to be moved downwardly with relation to the housing 22, due to the resistance of the drilling fluid in the well, and such downward movement of the disk, causes the wedges 36 to simultaneously engage the latch members 30 and force them out of the two notches 29 in the valve stems 25. Release of the two valve stems permits the springs 27 to instantly move the ring valve 24 downwardly to hermetically close the upper ends of the small vertical bores 20. Closure of the bores 20 acts to trap some air in each of the bores 16 above the liquid 21. The trapping of such air prevents any further flow of liquid in the bores 16 or in the groove 15 in the base fitting 14.

The device is next brought out of the well and the liquid levels in the bores 16 are observed.

The angle at which the device was disposed in the well at the time the valve 24 was closed, may be determined by tilting the device until the various liquid levels in the bores 16 are perfectly horizontal. Since the body 10 is transparent, the liquid levels may readily be observed.

From the foregoing description it is thought to be apparent that a device has been disclosed which is capable of accomplishing all of the objects and purposes for which it is intended.

Obviously, some changes in the construction of the device could well be made without detrimentally affecting its practicability, and I therefore do not wish to be confined to the preferred embodiment shown further than I am limited by the scope of the appended claims.

I claim:

1. An inclinometer, including: a transparent body having a series of radially spaced vertical open ended bores partially filled with liquid and communicating at their lower ends with a reservoir of said liquid; an air chamber communicating with the upper ends of said bores; a valve for securely closing said upper ends; means for holding said valve open as the device is lowered into a well; and means for selectively closing the valve for trapping air in said bores above said liquid.

2. Organization as described in claim 1, in which said valve holding means includes: a valve stem having a notch in its side; and a pivoted latch adapted to engage within the notch for holding the stem unmovable.

3. Organization as described in claim 1, in which said valve closing means includes: a spring urging the valve toward its closed position; and means actuated by movement of the device in the

well for submitting the valve to actuation by the spring.

4. Organization as described in claim 1, in which said valve holding means includes: a valve stem; and a latch adapted to engage the stem and hold the same immovable; and in which the valve closing means includes a spring urging the valve toward its closed position; and means actuated by movement of the device in the well for releasing the latch and submitting the valve to actuation by the spring.

5. An inclinometer, including a transparent body having a series of radially spaced vertical bores having both ends open; a reservoir connecting the lower ends of said bores; a liquid filling said reservoir and partially filling said bores; an air chamber communicating with the upper ends of said bores; a valve for securely closing said upper ends; means for holding said valve open as the device is lowered into a well; and means for selectively closing the valve for trapping air in said bores above said liquid.

6. An inclinometer, including a transparent body having a series of radially spaced vertical bores having both ends open; a reservoir connecting the lower ends of said bores; a liquid filling said reservoir and partially filling said bores; an air chamber communicating with the upper

ends of said bores; an annular valve in said chamber above said bores for securely closing their upper ends simultaneously; an upwardly extending valve stem carried by the valve and having a notch in one side; a pivoted latch adapted to engage within the notch for holding the stem immovable; a spring around the stem within the chamber for urging the valve toward a closed position; and means actuated by movement of the device in the well for releasing the latch and submitting the valve to actuation by the spring.

7. Organization as described in claim 6, in which the latch releasing means includes; a disk movable vertically with relation to the body by resistance of a well fluid; and a depending wedge adapted to release the latch when the disk is moved.
